US0D1094475S

(12) **United States Design Patent** (10) Patent No.: **US D1,094,475 S**
(45) Date of Patent: ** Sep. 23, 2025

(54) **HOOD OF A WORK VEHICLE**

(71) Applicant: **CNH Industrial Italia S.p.A.**, Turin (IT)

(72) Inventors: **Alessio Cadalora**, Modena (IT); **Jakub Maria Sulikowski**, Modena (IT); **John Piper**, Surprise, AZ (US)

(73) Assignee: **CNH Industrial Italia S.p.A.**, Turin (IT)

(**) Term: **15 Years**

(21) Appl. No.: **29/883,454**

(22) Filed: **Jan. 30, 2023**

(30) **Foreign Application Priority Data**

Jul. 28, 2022 (EM) 009098346
